(57) **CLAIM**

The ornamental design for a men's swimsuit with seamless back panel, as shown and described.

DESCRIPTION

FIG. 1 is a front perspective view of the men's swimsuit with seamless back panel of the present invention showing our new design;

FIG. 2 is a side elevational view thereof;

FIG. 3 is a rear view thereof;

FIG. 4 is a top plan view thereof; and

FIG. 5 is a bottom plan view thereof.

FIG. 6 is a front plan view of a second embodiment of the men's swimsuit with seamless back panel of the present invention showing our new design;

FIG. 7 is a side elevational view thereof;

FIG. 8 is a rear view thereof;

FIG. 9 is a top plan view thereof; and,

FIG. 10 is a bottom plan view thereof.

The dash-dot-dot-dash broken lines show drawstrings in FIGS. 1 and 6 that form no part of the claim. All remaining dash-dot-dot-dash broken lines shown in the figures depict stitching that forms no part of the claim.

1 Claim, 2 Drawing Sheets
